UNITED STATES PATENT OFFICE.

JAMES L. MARTIN, OF CROWELL, TEXAS.

WINDOW-OPERATING DEVICE.

Specification of Letters Patent. Patented Feb. 20, 1917.

1,217,040.

Application filed March 28, 1916. Serial No. 87,260.

To all whom it may concern:

Be it known that I, JAMES L. MARTIN, a citizen of the United States, residing at Crowell, in the county of Foard and State of Texas, have invented certain new and useful Improvements in Window-Operating Devices, of which the following is a specification.

This invention relates to improvements in window operating devices, particularly for street or railroad coach windows, one of the objects being to simplify the operation of the mechanism for opening and closing windows of this type and for locking the same in any position.

Another object resides in the provision of a window operating device embodying, among other characteristics, means whereby upon a rotative movement of an operating handle in opposite directions, devices may be operatively connected or disconnected to provide for an automatic raising and lowering of the window or to lock the same in adjusted positions.

Another object resides in the provision of a window operating device of the character stated wherein all of the operating mechanism, except the operating handle, is concealed in the framework of the car from the view of the operator, but to which access may be easily had for oiling, cleaning, repairing or the like, and in which the windows may be raised, lowered or adjusted in open position with comparatively little or no effort on the part of the operator.

With the above and other objects in view, the present invention consists in the combination and arrangement of parts hereinafter more fully described, illustrated in the accompanying drawings, and particularly pointed out in the appended claims, it being understood that changes may be made in the form, size, proportion and minor details without departing from the spirit or sacrificing any of the advantages of the invention.

In the drawings:—

Figure 1 is an elevation of a car window from the inside showing my device applied thereto.

Fig. 2 is a plan view of the operating mechanism of my invention, the sash, frame and weight being shown in section.

Fig. 3 is a vertical sectional view of my invention shown in connection with a car window, part of the sash and frame being broken away.

Fig. 4 is an elevation of the gear mechanism.

Fig. 5 is a section on the line 5—5 of 60

Fig. 4.

Fig. 6 is a section on the line 6—6 of Fig. 4.

Fig. 7 is a detail showing the bearing that supports the gear for moving the weight. 65

Referring now more particularly to the accompanying drawings, the reference character A indicates, in general, a portion of one side of the interior framework of a street or railroad car or other vehicle provided with spaced window openings in which are fitted the vertically sliding window sashes 10.

The spaces between the windows provide compartments 13 covered by removable panels *a* and *b* and each window has the usual guide rails 11 for the guidance of the respective window sash 10 adapted to slide upwardly above the upper ends of the guide rails 11 into the respective compartment 13. 80

On opposite sides of the compartment 13 may be disposed the stops 14 to limit the upward sliding movement of the window sashes. These stops may be of any particular construction but, as shown, are in the form of pins covered with rubber or other resilient material to prevent undue noise and to give a cushioning action when the window sashes are brought into contact with the stops. 85

A dash-pot C is located in each compartment 13, designed to act against the upward movement of each window, to prevent the elevating means for the windows, when released, from raising the latter too rapidly. One form of device for this purpose may be in the nature of an air cylinder 15 mounted in each compartment 13 and in which operates a piston 16 whose plunger 17 is secured to the upper side of the respective window sash 10 by means of suitable fastenings 18. 95 100

To raise each window against the respective dash-pot C, I provide a weight D for each window. The weight may be in the nature of a relatively long metallic bar provided at its upper end with an eye 19 to which a cord, chain or other cable 20 may be connected and which passes over pulleys 21 and 22 mounted in suitable brackets 21' and 22', respectively, in the framework of the car. This cable 20 has spaced connections 23 with the eyes or other fastenings 24 in the upper edge of the respective window sash 10. 110

The weight D is mounted for sliding move-

ment in a guide E in the respective compartment 13. This guide E may consist of a channeled member, as shown, and it is fixedly secured by bolts 27 or in any other 5 suitable manner between the inner and outer metallic casing plates 25 and 26, respectively, fixedly supported in any suitable manner in the respective compartment B between the windows.

10 The web of the channel shaped guide E is provided with upper and lower rollers 28 and 29 adapted to reduce friction between the guide and the weight and thereby facilitate a free and easy sliding movement of the latter in its guide. The weight D is provided with a gear rack 30 arranged preferably midway of the side edges thereof, and alongside of the gear rack 30 is a ratchet rack 31, the latter at one edge overlapping 15 the outer edge of one of the sides of the guide E, as shown particularly in Fig. 2 for the purpose of equally distributing the pressure of the weight D on the rollers 28 and 29 and for the further purpose of facilitating 20 an even guiding movement of the weight in its guide.

15 The weight D is held normally against downward movement by a suitable trip device. To this end, a trip arm 34 is swingingly mounted on a pivot 35 journaled in a hanger 37 depending from a bearing 38. This bearing 38 is fixed to the plate 25 by means of suitable pins 36 projecting from the bearing through suitable openings in plate 25 and by screw or other fastenings 40. A pawl 32 is pivotally secured at 33 to one end of the trip arm and this pawl is preferably case hardened and engaged by a spring 41 adapted to force the same normally in engagement with the teeth of the ratchet rack 31 on the weight D to prevent 45 accidental downward movement of the latter. A spring 42 is connected to an ear 43 on the trip arm 34 and to a lug 44 on the aforesaid fixed bearing 38 whereby the trip arm assumes such a position as to cause the pawl 32 to assume operative relation with the weight D for the purposes already stated.

50 A shaft 39 is journaled in said fixed bearing 38 and in the casing plates 25 and 26. An operating shaft 48 is journaled in the plates 25 and 26. These shafts 39 and 48 are connected together and to the weight D by a suitable gear mechanism. For instance, a gear 45 is keyed on the shaft 39 and disposed to normally mesh with the teeth of the aforesaid gear rack 30 on the weight D. A pinion 46 is also keyed on the shaft 39 adjacent said gear 45 and is 55 adapted to mesh with a gear 47 keyed on the operating shaft 48.

60 The operating shaft projects forwardly slightly beyond the front casing plate 25 and through an opening formed by the semi-circular openings a' and b' in the abutting

ends of the respective removable panels a and b of the car frame, projecting slightly beyond said panels. An operating handle 49 is loosely connected to the projecting end of the operating shaft 48, the handle having an integral collar 48' loosely embracing 70 said operating shaft.

A wheel 50 is secured to or formed with the collar 48' and it is provided with a tripping pin 51 adapted to slidably operate in a curved slot 52 in the front casing plate 25 through which said tripping pin projects and which also projects through a curved slot 52' formed in the aforesaid trip arm 34 provided with a throat 53 forming a shoulder 80 75 85 90 95 100 105 110 115 120 125 130

The panels a and b may be cut out to form a recess 55 between the inner faces thereof and the front plate 25 in which recess 55 the aforesaid wheel 50 is located and thereby concealed within the framework of the car. A ratchet wheel 56 is keyed on the operating shaft 48 immediately back of said wheel 50 and is therefore also located in said recess 55. A dog 57 is pivoted at 58 on the rear face of said wheel 50 and held normally in mesh with the teeth of said ratchet 56 by means of a suitable spring 59 connected thereto and loosely connected at one end to the aforesaid tripping pin 51 of 95 said wheel 50. This pin 51 is further connected by a spring 60 which has connection therewith and with the plate 25, suitable fastenings 62 securing said spring 60 to the plate 25. The purpose of this spring 60 is to maintain the operating handle 49 normally in a substantially vertical position and to maintain the pin 51 normally adjacent the throat 53 of the trip arm 34.

The spring 59 referred to is adapted to 105 normally hold the pawl 57 in engagement with the ratchet wheel 56 on the operating shaft 48 so that upon swinging movement of the operating lever to the right the lever which is loosely mounted on the shaft 48 110 may be caused to connect positively with said shaft 48 through the instrumentality of said ratchet 56 and the pawl 57 and thereby upon rocking or rotative movement given to the operating shaft 48 cause the 115 rotation of the gear 47 keyed on the operating shaft 48. The gear wheel 47, being in mesh with the pinion 46 on the shaft 39, gives rotation to the shaft 39 and to the gear 45 keyed on the shaft 39 and thereby 120 effects a lifting of the weight D to lower the window because of the gear 45 meshing with the gear rack 30 on the weight D.

The window may be lowered step by step, or entirely lowered, according to the manipulation of the handle 49. By oscillating the handle 49 between the limit of its swing to the right and its normal vertical position, the pawl 57 will be caused to intermittently engage with the teeth of the ratchet wheel 130

56 and thereby rotate the shaft 48 step by step and, by virtue of the gear connection between the shafts 48 and 39, cause upward movement of the weight D step by step and 5 a consequent step by step lowering of the window, whereby the window may be only partly lowered to an adjusted position or entirely lowered by a step by step movement. It is preferred, however, when it is desired 10 to entirely close the window, to give the operating handle 49 a complete swing to the right so that the gear mechanism between the shafts 48 and 39 and the weight D will cause the latter to travel the limit of its 15 movement under the influence of the gear mechanism to thereby completely close the window.

The swinging movement to the right of the operating handle 49 is limited by the engagement of the tripping pin 51 of the wheel 50 with the lower ends of the slots 52 and 52' in the casing plate 25 and trip arm 34, respectively. Immediately upon release of the operating handle 49 the spring 60 will 25 cause the operating handle and the parts actuated thereby to assume their normal positions.

To raise the window the weight D must be released by the pawl 32 of the trip arm 34 and the pawl 57 must be held from holding engagement with the ratchet wheel 56 on the handle collar 48'. To disconnect the pawl 32 from the ratchet bar 31 the operating handle 49 is grasped and turned from its 35 normally substantially vertical position to the left, which will give a rotative movement to the wheel 50 and a consequent shifting of the tripping pin 51 toward the upper end of the curved slot 52 in the plate 25 and 40 also toward the upper end of the slot 52' in the trip arm 34. To simply release the pawl 32 from engagement with the ratchet bar of the weight D is not sufficient because of the gear connection between the weight D and 45 the shafts 39 and 48. The locking relation of the gear mechanism, in view of the gear 50 being in mesh with the gear rack of the weight D will prevent fall of the latter because of the pawl 57 engaging the ratchet 55 wheel 56 on the operating shaft 48 and preventing rotation of the latter. It is therefore necessary that the pawl 57 be released from holding relation with the ratchet wheel 56 simultaneously with the release of the 60 pawl 32 from engagement with the gear rack 30 of the weight D. A pin 57' is therefore secured to the casing plate 25 between the ratchet wheel 56 and the pawl 57 so that as the wheel 50 which carries the pawl 57 is 65 given a rotative movement under the influence of movement of the operating handle 49 to the left, the pawl 57 is caused to ride over this pin 57' and thereby become disengaged from the teeth of the ratchet wheel 57 against the action of the spring 59.

Thus as the tripping pin 51 is shifted in the manner stated toward the upper ends of the slots 52 and 52' in the plate 25 and trip arm 34, respectively, the tripping pin 51 rocks the trip arm 34 on its pivot 35 and withdraws the pawl 32 from engagement 70 with the gear rack 30 of the weight D. At the same time the pawl 57 rides on the pin 57' and is therefore lifted away from the ratchet wheel 56 to release the aforesaid 75 gear mechanism, with the result that the weight D may fall and, by virtue of the cable connection between the weight and the window the latter may be raised under the influence of the weight D against the action 80 of the dash-pot C. As the weight D falls, and the pawl 57 having been disengaged from the ratchet wheel 56 by virtue of its riding over the pin 57', as stated, the gear mechanism between the gear rack 30 and the 85 operating shaft 48 may be actuated to give a rotative movement to the operating shaft 48. This rotative movement of the shaft 48 is independent of movement of the trip arm tripping means including the handle, 90 the wheel 50, the sleeve 48', and the pin 31, because these parts of the tripping device are all connected together and have loose connection with the operating shaft 48, as 95 before stated.

Thus, by virtue of operating the handle 49 to the left, the pawls 32 and 57 are tripped from operative relation with the weight D and the ratchet wheel 56, respectively, with the result that the weight D falls, and by virtue of the cable connection 20 with the respective window the latter is consequently pulled upon and elevated into engagement with the aforesaid stops 14 in the compartment B. This downward movement 100 of the weight D may be quickly arrested by release on a backward swing of the operating handle 49 to or toward its normally vertical position, whereby the window may be elevated part way or entirely raised, as may 110 be desired.

My improved window operating device is equally applicable for the raising and lowering of large or small windows in residences or other buildings, and I do not wish to be 115 limited in the use of my window operating device to those of the car type.

What is claimed is:—

1. In a window operating device, a frame, a window sash slideable in the frame, a weight 120 to slide the sash, means to prevent accidental movement of the weight in one direction, a swingingly mounted handle, and connections between the handle and the weight, whereby upon movement of the handle within certain limits the weight is moved in one direction to permit movement of the window sash and whereby, when the handle is moved within certain other limits, said holding means is released to permit 130

the weight to move in the opposite direction and thereby move the window sash in a direction opposite to its aforesaid movement.

5. 2. In a window operating device, a frame, a window sash vertically slidable in the frame, a weight operatively connected to the window sash, a swingingly mounted handle disposed normally in a vertical plane, and connections between the handle and the weight whereby movements of the handle between its normal and vertical position and the limit of its swing in one direction will permit movement of the weight to raise 10 the window to any desired extent and whereby upon movement of the handle between its normal vertical position and the opposite limit of its swing will permit the weight to move in the opposite direction to lower 15 the window to any desired extent.
3. In a window operating device, a frame, a window sash vertically slidable in the frame, a weight vertically slidable and operatively connected to the window sash, 20 means for holding the weight against accidental downward movement, a swingingly mounted handle disposed normally in a vertical plane, and connections between the handle and the weight, whereby quick backward 25 and forward movement of the handle between its normal position and the limit of its swing in one direction, will release said holding means, and effect a step by step downward movement of the weight to raise 30 the window step by step and whereby a quick backward and forward movement of the handle between its normal vertical position and the opposite limit of its swing will effect a step by step upward movement of 35 the weight and thereby permit the window to lower step by step.
4. In a window operating device, a frame, a window sash vertically slidable in the frame and operatively connected to the window sash whereby the window sash is raised 40 and lowered according to the direction of movement of the weight, a trip arm to hold the weight against accidental downward 45 movement, and means, including a handle, operable to raise the weight to lower the sash, said handle being operable to simultaneously release said trip arm from holding engagement with the weight and to actuate said weight raising means to permit 50 downward movement of the weight to raise the window.
5. In a window operating device, a frame, a window sash vertically slidable in the frame, a weight vertically slidable in the frame and operatively connected to the window sash whereby the window sash is raised 55 and lowered, according to the direction of movement of the weight, means to hold the weight and thereby prevent downward 60 movement, and means operable to raise the weight to lower the sash, said handle being operable to simultaneously release said trip arm from holding engagement with the weight and to actuate said weight raising means to permit 65 downward movement of the weight to raise the window.

movement of the weight, and means operable to raise the weight to lower the sash, and including a pawl and ratchet mechanism to simultaneously release said holding means and said weight raising means to 70 lower the weight and raise the window.

6. In a window operating device, a frame, a window sash vertically slidable in the frame, a weight vertically slidable in the frame and operatively connected to the window sash, whereby the window sash is raised and lowered according to the direction of movement of the weight, a trip arm journaled in the frame and held normally in engagement with the weight to prevent 80 downward movement of the latter, and means operable to raise the weight to permit the sash to lower and also operable to simultaneously release said trip arm from operative connection with the weight and also 85 release said weight raising means to inactive operation so as to lower the weight and thereby raise the window.

7. In a window operating device, a frame, a window sash vertically slidable in the frame, a weight vertically slidable in the frame and operatively connected to the window sash whereby the window sash is raised and lowered according to the direction of movement of the weight, a gear rack on the weight, a ratchet rack on the weight, a trip arm pivotally mounted in the frame and carrying a pawl adapted to normally engage said ratchet rack to prevent accidental downward movement of the weight, a gear mechanism mounted in the frame and having operable connection with said gear rack to raise the weight to permit the sash to lower, and means operatively connected to said gear mechanism and to said trip arm to disconnect the trip arm pawl from the ratchet rack and to permit inactive operation of the gear mechanism so as to lower the weight and thereby raise the window and subsequently operable to throw the trip arm pawl 100 into engagement with the ratchet rack and to positively actuate the gear mechanism to raise the weight and thereby permit the window to lower.

8. In a window operating device, a frame, a window sash vertically slidable in the frame, a weight vertically slidable in the frame and operatively connected to the window sash, means to hold the weight against accidental downward movement and thereby 115 prevent accidental raising of the window, a rotative shaft journaled in the frame, a gear mechanism operatively connecting the weight and the said shaft, a handle loosely connected to said shaft, a pawl and ratchet 120 to positively connect said handle to said shaft whereby upon operation of the handle in one direction said shaft is given a rotative movement to operate the gear mechanism and thereby raise the weight to permit 125 130

the window to lower and means whereby upon operation of the handle in the opposite direction said holding means is disconnected from operative relation with the weight and 5 said pawl and ratchet also disconnected so as to permit the weight to fall and the gear mechanism to take inactive operation under the influence of the falling movement of the weight and thereby raise the window.

10 9. In a window operating device, a frame, a window sash vertically slidable in the frame, a weight vertically slidable in the frame and operatively connected to the window sash whereby the window sash is raised 15 and lowered according to the direction of movement of the weight, means to prevent accidental downward movement of the weight, means operable to raise the weight to permit the sash to lower and means to simultaneously release the aforesaid holding 20 means and said weight raising means to thereby lower the weight and raise the window and subsequently operable to actuate said weight raising means to raise the 25 weight and thereby permit the window to lower and means connected to the window sash to control the speed of upward movement of the same.

10 10. In a window operating device, a vertically slidable window sash, a vertically slidable weight having operative connection with the window sash so as to permit the sash to raise and lower according to the direction of movement of the weight, means 35 for holding the weight against accidental downward movement, means to release said weight and to actuate said releasing means to entirely raise the window or raise it step by step, and means operable to raise said 40 weight to permit the window to lower entirely or step by step.

11. In a window operating device, a vertically slidable window sash, a vertically slidable weight having operative connection 45 with the window sash so as to permit the sash to raise and lower according to the direction of movement of the weight, means for holding the weight against accidental downward movement, means to release said 50 weight and to actuate said releasing means to entirely raise the window or raise it step by step, means operable to raise said weight to permit the window to lower entirely or step by step, and means connected to the 55 sash to control the speed of upward movement of the sash.

12. In a window operating device, a frame, a window sash slidable in the frame, a weight slidable in the frame and operatively connected to the window sash, a gear rack on said weight, spaced shafts rotatively mounted in the frame, a gear mechanism connecting the shafts and operatively con-

nected to said gear rack, a handle loosely connected to one of said shafts and lying 65 normally in a substantially vertical plane, means operable to lock the handle to the shaft to which it is connected so that upon movement of the handle in one direction said gear mechanism will raise the weight 70 and thereby permit the window sash to lower, means to hold the weight against accidental downward movement, and means to simultaneously release said weight holding means and to permit inactive operation 75 of said gear mechanism so as to permit the weight to move downward and thereby raise the window.

13. In a window operating device, a window sash vertically slidable in the frame, 80 a weight vertically slidable in the frame and operatively connected to the window sash, means to raise the weight to permit the sash to lower, means for holding the weight against accidental downward movement, and means to simultaneously release 85 said holding means and render the weight raising means operatively inactive with relation to the weight so as to permit lowering of the latter and a consequent raising of 90 the sash.

14. In a window operating device, a frame, a window vertically slidable in the frame, a weight vertically slidable in the frame and operatively connected to the window sash, and means, including a swingingly mounted handle whereby upon swinging movement of said handle within certain limits on one side of the axis on which the handle is swingingly mounted, the weight 95 may move upwardly to lower the sash and when the handle is swung within certain limits on the opposite side of the axis on which it is swingingly mounted, the weight 100 may move downwardly to raise the window 105 sash.

15. In a window operating device, a frame, a window sash vertically slidable in the frame, a weight vertically slidable in the frame and operatively connected to the window sash, a swingingly mounted handle, and means operatively connected to the handle whereby upon swinging movement of said handle on one side of the axis on which the handle is swingingly mounted the weight 110 may be moved upwardly to effect the lowering of the window sash and when the handle is swung within certain limits on the opposite side of its axis the weight may move 115 downwardly to effect a raising of the window sash, and means for holding the window sash at different elevations in the frame, said latter means being under the control of said handle.

In testimony whereof I affix my signature. 125
JAMES L. MARTIN.
